UNITED STATES PATENT OFFICE.

JOHN EDMUND FERRY, OF SHARON, PENNSYLVANIA, ASSIGNOR TO VALLEY MOULD & IRON CORPORATION, OF SHARPSVILLE, PENNSYLVANIA, A CORPORATION OF NEW YORK.

CORE BAR.

Application filed April 27, 1925. Serial No. 25,964.

This invention relates broadly to metallurgy and more especially to a collapsible core bar particularly adapted for the casting of ingot molds or the like.

5 Various types of core bars have heretofore been proposed to facilitate the removal of the bar when stripping the mold, and to this end, various collapsible constructions have been designed, but in such collapsible structures a sliding movement of the core bar relative to the inside wall of the casting has heretofore been necessary before the collapsible mechanism is operative.

In the present case, the core bar is designed 15 in such manner as to allow the direct inward movement of the side walls of the core bar without requiring any preliminary sliding movement or endwise movement of such side walls relatively to the casting.

20 Furthermore, the side plates forming the side walls of the present core bar are spaced from the cone or central post in such manner as to provide passage ways through which the mold gases may freely escape, 25 thereby producing a better surface on the interior of the casting and also permitting the cooling down of the cast mold on the interior thereof at the proper rate to produce proper stress conditions conducive to 30 a long lived ingot mold.

Another feature of the present invention is the formation of the vent holes in the side plates in such manner as to support the mold sand carried by these side plates.

35 With the present invention, cast molds may be stripped earlier than is possible where core bars are used which require a sliding movement between the core bar and the ingot mold, because where such prior 40 art types of core bars are used there is a liability of cracking or disturbing the inner skin of the ingot mold unless the mold is permitted to thoroughly cool or harden before the stripping operation occurs. This 45 tends to tie up equipment and slows up manufacturing operations. With the present core bar, the bar may be collapsed as quickly as the cast mold is hardened sufficiently so that the mold will not bleed. This 50 is because of the fact that in stripping the present core bar the side walls of the bar move directly inwardly so that they merely take away the supporting surface from behind the mold sand and do not slide longitudinally relatively to the mold side walls

during the initial releasing action. This releases equipment for further manufacture and also facilitates cooling of the mold.

The principal object of the present invention is a collapsible core bar adapted for 60 the manufacture of ingot molds and constructed in such manner that the controlling bar or cone bar may be moved to permit collapsing of the side plates without an initial longitudinal movement of the side 65 plates.

Another object of the present invention, is a core bar provided with venting spaces back of the side plates in such manner as to 70 vent the mold gases through the interior of the core bar, and also where desired to permit an air flow through the core bar.

A still further object of the present invention is a core bar provided with vent openings in the side plates constructed in such 75 manner so as to support the mold sand during the set up and at the same time permit the sand to break away from the side plates when the core bar is collapsed.

A still further and important object of 80 the present invention is a core bar constructed in such manner that the side plates thereof are provided with longitudinal strengthening ribs to prevent warping of said plates when said core bar is subjected 85 to the intense heat of molten metal during casting operations.

A still further object of the present invention is a core bar of the character specified in which longitudinal ribs on the side 90 plates are supported by transverse bars which cooperate with control wedges on the control bar whereby said side plates are solidly supported during casting operation, and whereby each side plate is independently 95 supported.

Another and further object of this present invention is a core bar in which both the side plates and the control cone are carried by a stationary supporting column. 100

Realizing that the present invention may be embodied in constructions other than those specifically disclosed herewith, it is desired that this disclosure shall be considered as illustrative and not in the limiting sense.

Throughout the drawings like parts are designated by like characters.

Figure 1 is an elevational view of the preferred form of the core bar set on a cast- 110

ing base and showing the vent openings in the top and side plates.

Figure 9 is a section on line 9-9 of Fig. 8, showing the arrangement of vent openings at the corners of the side plates.

Figure 10 is a top plan view of the device.

20 Figure 10 is a top plan view of the device shown in Figure 1.

Figure 11 is a bottom plan view of the core bar shown in Figure 1.

The preferred embodiment of the present invention comprises a collapsible core bar which is built around and upon a supporting column 1, that is hollow, and in the preferred form has a cross-section of the general shape of a Greek cross. In the form shown, the cross-section of the complete core bar is rectangular, and the supporting column is, therefore, longer than it is wide. Openings 2 are provided at suitable intervals through the end extensions 4. In the illustrated construction, there are three of these openings. These openings 2 are adapted to receive expansion bars 5 and to permit a limited movement of these bars toward and from the axis of the core bar whereby the expansion or collapse of the core bar is controlled, as will be later explained. These expansion bars 5 are mounted on projections 6 extending from the outer side plates 7, which projections enclose the end extensions 4. Suitable bolts 8 may be utilized for attaching the expansion bars 5 to the side plates 7. The outer side plates 7 are provided with longitudinally extending ribs 9 that extend the complete length of the side plates and serve as strengthening members to prevent warping of the plates and also as means for transmitting forces acting on the expansion bars to the entire side plates. The edges of the side plates are curved as at 10 to form corners of the core bar.

The side portions of the supporting column 1 are pierced by pairs of openings 11 through which projections 12 from the inner side plates 14 extend. These projections 12 carry expansion bars 15, which are suitably bolted to the inner side plates 14 to rigidly interlock with the same. These inner side plates 14 are likewise provided with longitudinally extending ribs 16 for the same

purpose as the similar ribs on side plates 7. The edges of the inner side plates 14 are curved as at 17 and adapted to lock under the corner projections 10 on the outer side plates 7. It will be observed that both sets of expansion bars 5 and 15 are exposed within the hollow portion of the supporting column 1 and are capable of limited movements toward and from the axis of the core bar, and at the same time, serve as interlocking members which securely interlock both pairs of side plates to the supporting column and prevent endwise movement of the side plates relatively to the supporting column.

A controlling cone or wedge member 18 is mounted within the hollow in the supporting column and in cross-section is similar to the shape of the cross-section of the column so that this supporting bar or control cone conforms to the shape of the column and the surfaces at the corners 19 are substantially parallel and cooperate with similar substantially parallel corners 20 forming the inner projecting corners of the supporting column 1. This construction permits of a longitudinal movement of the controlling cone or wedge member in the supporting column. The faces 21 on the control cone 18 are inclined in opposite directions and toward the axis of the controlling cone. These faces are adapted to engage the expansion bars 5 while the faces 22 on the controlling cone 18, and which are similarly oppositely inclined toward the axis of the core bar, cooperate with the expansion bars 15. Where desired, the inclination on the faces 22 may be slightly greater than the inclination on the faces 21 so that the inner side plates 14 may be relieved at a slightly greater rate than the outer side plates 7 to permit proper clearance between the corners 10 and the curved edges 17. The control cone 18 preferably is provided with a ventilating opening 23 which leads to openings 24 in the top of the control cone and the side plates 7 and 14 are spaced a sufficient distance from the supporting column 1 to provide longitudinal ventilating conduits 25 whereby proper ventilation is at all times provided for the entire core bar 110

at all times provided for the entire core bar structure. The top of the supporting column 1 is provided with a head 26 formed with guide lugs 27 which guide the upper end of the control cone 18. Ventilating spaces 28 are provided between the lugs 27 and these spaces lead to the interior of the core bar. This head is also formed with an overhang 29, which prevents mold sand from filling up the ventilating spaces in the core bar when the bar is being covered with sand by ramming the sand around the same in a suitable core box. The top portion of the head 26 serves as a support for the wedge key 30, which may be driven through a suitable opening in the extension 31 form- 120 125 130

ing the handle to the core bar on the upper end of the controlling cone 18. When this wedge key 30 is driven in place, the side plates 7 and 14 are wedged outwardly to their extreme position and are securely locked with the core bar fully expanded, so that it is ready for the sand ramming operation. Preferably, bottom edges of the side plates 7 and 14 do not extend downwardly to the bottom plane on the lower end of the supporting column, which forms the basis of the core bar, and preferably the central portion of the side plates is slightly undercut, as at 32. This undercutting and shortness of the side plates permits sand to extend slightly beneath the end of the side plates and cover the same to prevent undue heating of the side plates by contact of molten metal therewith. The base of the core bar is filled in at the corners 34 of the base of the column 1 and forms anchors for bolts 35 that attach the base 36 to the column 1 which comprises the support for the core bar. This core bar base 36 is adapted to set on the casting bottom and center the core bar in the flask and mold, and is provided with a draft opening 33 through which air may be admitted as desired to circulate through the conduit 23 and out through the spaces 28.

A feature of the present invention is the formation and shape of the vent holes 37 in the side plates and other portions of this core bar. These vent holes 37 preferably comprise a substantially horizontal bottom portion 38 and a funnel-shaped mouth 39, which may lead to a cylindrical opening 40. The funnel-shaped mouth with its upward inclination is so arranged that when mold sand is rammed around the core bar, the sand 41 tends to enter the vent opening and interlock the sand with the side plates. The inclination of the upper part of the mouth of the vent openings facilitates the entry of the sand into the openings during the ramming of the sand downwardly past the faces of the side plates or between the faces of the side plates and a suitable core box, while the horizontal portion of the vent openings acts to support the sand and prevents its dropping from the face plates. According to the present invention lines of vent openings are arranged in the corners of the side plates and with the axes of these openings substantially directed toward the longitudinal axis of the core bar. The most difficult part of the core bar mold sand to vent is that portion surrounding the corner of the core bar, and it has been found that this arrangement of corner openings effectively vents this area.

It will be observed that in the present construction each side plate is independently supported in such manner that there is no tendency of an accidental general collapse of the core bar when the metal begins to cool

and impose compression forces upon the core bar when the core bar is in use. Furthermore, it will be observed that during the collapsing of the core bar the supporting column has no longitudinal movement. The control cone 18 is caused to release the wedging action on the expansion bars when desired, thereby permitting the side plates to move inwardly toward the longitudinal axis of the core bar, and, therefore the only movement of the side plates during the collapsing action in an inward bodily movement, which does not impose objectionable forces on the ingot mold that has been cast around the core bar.

Furthermore, it will be observed that the ventilating spaces heretofore referred to permit the green mold sand packed around the core bar to be effectively and quickly dried and baked, since heated air or gas reach not only the face of the mold sand, but may circulate over the entire backs of the face plates.

And finally, these ventilating conduits quickly carry off heated air of mold gases formed during the use of the core bar and where desired may permit an upward draught of cooled air to circulate through the core bar, which tends to quickly cool down the core bar itself and the interior of the casting whereby the core bar may be removed more quickly than heretofore permissible thereby releasing this equipment for more immediate use than has heretofore been the practice.

Having thus described my invention, what I claim is:

1. In a collapsible core bar, the combination of a supporting column, a base secured to said supporting column, a plurality of side plates adapted for to and fro movement relative to the axis of the supporting column, and means within said supporting column to control said to and fro movement of said side plates.

2. In a collapsible core bar for making substantially rectangular ingot molds, the combination of a base, a supporting column, mounted on said base, a plurality of substantially flat side plates adapted for to and fro movement relative to the axis of the supporting column, and wedge means within said supporting column to control said to and fro movement of said side plates, there being individual wedge means for each side plate.

3. In a core bar, the combination of a supporting column provided with openings in the side walls thereof, a plurality of movable side plates carried by said supporting column, operating means attached to said side plates and extending through said openings, a control member mounted in said supporting column and operative upon said means to control the movement of said side plates.

4. In a core bar, the combination of a stationary supporting column provided with openings in the side walls thereof, a plurality of movable side plates carried by said supporting column, operating means attached to said side plates and extending through said openings, a movable control member mounted within said supporting column operative upon said means to control the movement of said side plates, and ventilating means for the body of the core bar.
5. A core bar comprising a hollow supporting column, a plurality of movable side plates carried by said supporting column, guide means attached to said side plates and extending into the opening in said hollow supporting column, a longitudinally movable controlling member cooperative with said guide means to control the movement of said side plates.
6. A core bar comprising a supporting column, a plurality of movable side plates mounted on said column, guide lugs extending from said side plates through said supporting column, stop means carried by said lugs and adapted to contact with the column to limit the outward movement of said plates and a control bar adapted to control the movement of said side plates, and to lock said side plates in their outermost stopped positions.
7. A core bar comprising a supporting column, a plurality of movable side plates mounted on said column, guide lugs extending from said side plates through said supporting column, stop means carried by said lugs and adapted to contact with the column to limit the outward movement of said plates, and a wedge control bar adapted to act upon said means to control the movement of said side plate, and a wedge key operative upon the control bar and the column to lock said side plates in their outermost stopped positions.
8. A core bar comprising a supporting column, a plurality of movable side plates carried by said supporting column, expansion bars on the interior of said column and connected to said side plates, and a longitudinally movable control bar provided with wedge surfaces adapted to contact with said expansion bars to force said side plates outwardly.
9. A core bar comprising a supporting column, a plurality of movable side plates carried by said supporting column, expansion bars on the interior of said column and connected to said side plates, and a longitudinally movable control bar guided by the supporting column and provided with wedge surfaces adapted to contact with said expansion bars to force said side plates outwardly.
10. A core bar comprising a supporting column, side plates relatively movable to said supporting column, a movable wedge shaped member adapted to force said side plates outwardly, and means to lock said side plates in their outermost positions.
11. A core bar comprising stationary supporting means, side plates relatively movable to said supporting means, and a movable wedge shaped member guided by said supporting means and adapted to force said side plates outwardly, and means to lock said side plates in their outermost positions.
12. A core bar provided with a hollow supporting column, a plurality of side plates movably mounted upon said column, means to control the movement of said side plates, and a ventilating chimney portion connected with and extending above the body of said supporting column.
13. A core bar provided with a hollow supporting column, a plurality of side plates movably mounted upon said column, longitudinal guide ribs on the said plates, means to control the movement of said side plates, and a ventilating chimney portion connected with and extending above the body of said supporting column.
14. A core bar comprising a supporting column, a plurality of movable side plates mounted upon said supporting column, said parts being constructed and arranged to provide ventilating spaces around said side plates and within said supporting column, and means to carry away the mold gases arising through said ventilation openings.
15. A core bar comprising a hollow supporting column, a base attached to said supporting column and provided with an opening leading to the opening in said column, a head chimney portion upon said column and connected with the interior thereof, side plates spaced apart from said supporting column to provide ventilating spaces back of said side plates, said side plates being provided with vent openings leading to said ventilating spaces, and conduits in the side wall of said supporting column to lead said vent gases into the interior of said supporting column and out through the chimney portion thereof.
16. A core bar comprising a plurality of vented sides, a hollow chimney portion above said vented sides, and means for conducting mold gases from the back of said sides out through said chimney portion.
17. A core bar comprising a plurality of sides provided with vent openings, a hollow head portion extending above said sides and provided with a ventilation opening adapted to carry away mold gases driven into the interior of said core bar through the vent openings in the side plates.
18. A core bar comprising a plurality of vented side plates, a base provided with a ventilation opening, a top portion extending above said side plates and being pro-

vided with a ventilating conduit adapted to carry away mold gases driven into the interior of said core bar and to permit an upward draught of air through the core bar to facilitate the discharge of said mold gases from the interior of said core bar.

19. A core bar comprising a hollow supporting column, a plurality of vented side plates movably mounted on said core bar, lugs extending from said side plates through the side walls of said supporting column, bars within said column and mounted upon said lugs, a hollow sliding wedge member cooperating with said bars to control the movement of said side plates and clamp the bars against the interior of the column, and a locking device to lock said parts in expanded position.

20. A core bar comprising a supporting column provided with a head portion forming a protecting overhanging member, a plurality of movable side plates mounted beneath the overhanging parts of said head portion, and means to provide lateral movement of said side plates.

21. A core bar comprising a supporting column provided with stop faces, a plurality of movable side plates mounted upon said supporting column, expansion bars adapted to be brought against said stop faces to maintain the side plates in expanded position, and means cooperative with said expansion bars to lock the same tightly against said stop faces.

22. A core bar comprising a stationary hollow supporting column provided with stop faces, a plurality of movable side plates mounted upon said supporting column, expansion bars having portions within the column and adapted to be brought against said stop faces to maintain the side plates in expanded position, and slideable wedge means guided by the column and cooperative with said expansion bars to lock the same tightly against said stop faces.

23. A core bar comprising a supporting column, a plurality of movable side plates supported by said column, stop faces on the interior of said column, expansion bars connected with said side plates, and wedge means adapted to lock said expansion bars against the stop faces on the interior of said supporting column.

24. A core bar comprising a hollow supporting column, a plurality of movable side plates guided by and supported by said column, stop faces on the interior of said column, expansion bars connected with said side plates, and slideable wedge means within said column and adapted to lock said expansion bars against the stop faces on the interior of said supporting column to securely hold the parts in position during use.

25. In a collapsible core bar, a base, and a plurality of movable side plates having 65 their lower ends adjacent the upper surface of said base, said side plates being provided with under-cut portions adjacent the lower ends thereof to form sand retaining recesses.

26. A collapsible core bar comprising a 70 plurality of movable side members, a control bar for operating said side members, a ventilating head surrounding the upper end of said control bar and provided with a plurality of guiding ribs adapted to guide the up- 75 per end of said control bar.

27. As an article of manufacture, a support for a core bar comprising side members provided with openings adapted to guide 80 side plates and having an overhanging top 80 portion comprising a chimney for carrying off mold gases when said core bar is in use.

28. A core bar comprising a supporting column, a plurality of movable side plates mounted on said supporting column, guiding 85 means on said supporting column cooperating with guiding members on said side plates to guide said side plates during their movement, a control member slideable in said supporting column and adapted to be guided by said supporting column during its movement, and means for locking said control member in position to lock said side plates in their expanded relation.

29. As an article of manufacture, a core 95 bar having the sides thereof provided with vent sand openings having the upper part of said openings inclined upwardly and outwardly.

30. As an article of manufacture, a core 100 bar having the side plates thereof vented with sand openings, said sand openings having the upper portion thereof extending outwardly and upwardly and the lower portion of said openings being substantially horizontal.

31. As an article of manufacture, a core 110 bar provided with vent openings with the outer end thereof being substantially oval and the inner end being substantially circular.

32. As an article of manufacture, a core bar provided with vent openings with the outer ends thereof enlarged to form sand retaining recesses.

33. As an article of manufacture, a core 115 bar provided with a row of vent openings in the corners thereof and with the outer ends thereof enlarged to form sand retaining recesses.

34. As an article of manufacture, a core bar with vent openings in the corners thereof and with the axes of the vent openings directed toward the axis of the core bar.
